(57) **CLAIM**

The ornamental design for a check scanner with printer, as shown and described.

DESCRIPTION

FIG. 1 is a perspective view of a check scanner with printer, as viewed from the top, front and right side, embodying our new design;

FIG. 2 is a perspective view thereof, as viewed from the top, rear and left side;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a left side view thereof, shown with a portion cut-away for clarity of illustration.

The broken lines are for illustrative purposes only and form no part of the claimed invention.
